CLAIM

The ornamental design for a kiosk as shown and described.

DESCRIPTION

FIG. 1 is a front perspective view of the kiosk showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a partial enlargement view of portion 9 shown in FIG. 2;

FIG. 10 is a partial enlargement view of portion 10 shown in FIG. 3;

FIG. 11 is a partial enlargement view of portion 11 shown in FIG. 3;

FIG. 12 is a partial enlargement view of portion 12 shown in FIG. 3;

FIG. 13 is a partial enlargement view of portion 13 shown in FIG. 3;

FIG. 14 is a partial enlargement view of portion 14 shown in FIG. 3;

FIG. 15 is a partial enlargement view of portion 15 shown in FIG. 3; and,

FIG. 16 is a partial enlargement view of portion shown in FIG. 7.

The portions of the kiosk shown in broken lines in the drawing are for illustrative purposes only and form no part of the claimed design. Surfaces shown between the broken lines and the solid lines are included in the claim.

1 Claim, 14 Drawing Sheets
